INVENTOR
W. L. FLEISHER.

B. J. Fosse
ATTORNEY

UNITED STATES PATENT OFFICE.

WALTER L. FLEISHER, OF NEW YORK, N. Y.

BAKERY PROOF BOX.

Application filed August 4, 1925. Serial No. 48,176.

To all whom it may concern:

Be it known that I, WALTER L. FLEISHER, a citizen of the United States, and a resident of the county of New York, city of New York, and State of New York, have invented 5 a new and useful Bakery Proof Box, of which the following is a specification.

My invention relates to bakery proof boxes built in units with air inlets and outlets 10 so arranged that the box can be set up, enlarged or reduced without any changes except as to its size.

The object of the invention is to provide 15 a bakery proof box built of units so that all parts are interchangeable, and with the air inlets and outlets arranged for the best method of proofing.

In the appended drawing, Figure 1 is a 20 top plan view of two units combined to form a proof box. The dotted outline in said figure shows an added third section. Figure 2 is a fragmentary section on line 2/2, Figure 1. Figure 3 is a vertical section on line 3/3, Figure 1, and Figure 4 is an enlarged modified structure of the air duct 25 in the proof box unit.

Referring to the drawings, 5—5 are sections or units of which the proof box is 30 formed. Each of the units comprises a vertical air duct portion 6 merging into horizontal duct portions 7. The air duct is preferably framed by channeled shape 8. See Figures 1 and 4. The ducts in each unit are located on the opposite walls of the 35 facing units forming the proof box. The walls of the unit are preferably formed of double walled panels 9, the inside facing or sheeting of which is preferably of non-corrosive material.

40 The roof is also formed of double panels 10, but the inner facing is of the same metal as the outer facing, for a hanging ceiling 11 of non-corrosive material is provided in each unit, the space between the panels 10 and 45 the ceiling 11 forming a plenary chamber 12 which is in communication with the interior of the unit by adjustable dampers 13 provided in the ceiling.

In the structure shown in Figures 1, 2 50 and 3, the panels 9 at the channeled shape 8 form the rear wall of the air ducts, the front walls of the unit being formed by plates 14 located in the vertical part of the duct 6 and plate 15 covering the horizontal duct portions 7. The plates 15 are pro-

vided with suitable apertures 16 through which air is distributed to the box formed of the units 5.

In the modified structure of Figure 4, the air duct proper is formed of rectangular 60 sections 17 which are fitted between channeled shapes 8.

When another section is to be added to form a larger proof box, as shown in dash and dotted line in Figure 1, the panels 9 65 of the adjacent existing unit are removed as well as the plates 14 and 15 of the unit or the rectangular unit 17 if the structure of the duct is such as shown in Figure 4. The panels can then be used on the new 70 added unit as well as the plates 14 and 15 or the rectangular duct 17. In consequence, the outer side wall of the new unit is closed by the panels of the preceding unit and the air duct thereof is formed by the plates or 75 rectangular duct 17 of the same preceding unit. The preceding unit adjacent thereto will have its original outer wall merely outlined by the structural shapes used for its construction in addition to the channeled 80 shapes 8 which originally framed the air duct.

In view of the fact that the channeled shapes 8 are open where originally the air duct was formed, very little resistance will 85 be offered to the flow of the air from the new air duct provided in the outer side wall of the added unit. The new added unit has its own plenary chamber which will form an extension of the plenary chamber of the 90 other units to which the new unit is connected.

In some cases the openings 16 of the air duct may have to be changed where the 95 number of units added is large and the volume of the box is increased considerably.

Each section is provided with doors 18 through which the trucks are moved and in cases where sections are added to the sides where the doors are provided, it is only 100 necessary to remove the doors and panels of the said sides, add the units and place the doors and panels removed on the new units. The new added units will have the horizontal portions of the air ducts either merged with 105 the horizontal portions of the adjacent units or independent thereof.

From the above description it will be seen that in my construction of the proof box 110 of standardized unit or sections, a proof

box can be built of a definite size and then increased or decreased by a definite unit or units, as the case may be.

I claim:

- 5 1. In a proof box formed of units or sections, each having a plenary chamber at the top thereof, channelled shapes disposed along a vertical wall for framing an air duct and means interposed between the section and the plenary chamber for controlling the communication therebetween.
- 10 2. In a proof box formed of units or sections, each having a plenary chamber at the top thereof, a removable air duct disposed along a vertical wall of the section, means for supporting the duct forming part of the wall structure, and means interposed between the plenary chamber and the section below the plenary chamber for controlling the flow of air therebetween.
- 15 3. In a proof box formed of units or sections, each unit having a removable air duct presenting a vertical portion on the side wall and a horizontal portion on the same wall near the bottom of the chamber,

said vertical and horizontal duct sections being framed by channelled shapes forming part of the said side wall.

4. In a proof box formed of units or sections, each unit having channelled shapes running along the side wall in substantially vertical and horizontal directions, and means for engaging the said shapes to form an air duct for the unit. 30

5. In a proof box formed of units or sections, each having a hanging ceiling spaced from the top of the unit to form a plenary chamber in the unit, channelled shapes running along a side wall of a unit in substantially vertical and horizontal directions, the vertical parts of such shapes passing through the plenary chamber, while the horizontal parts are located substantially at the bottom of the unit, means co-operating with said channelled shapes to form an air duct for the unit, and means associated with the hanging ceiling for controlling the air flow from the duct to the plenary chamber. 35 40 45

WALTER L. FLEISHER.
